WARREN G. KELLOW, OF LOS ANGELES, CALIFORNIA.

ADJUSTABLE EYE-TILTING DEVICE FOR DOLLS.

1,312,447.

Specification of Letters Patent.

Patented Aug. 5, 1919.

Application filed August 12, 1918. Serial No. 249,511.

To all whom it may concern:

Be it known that I, WARREN G. KELLOW, a citizen of the United States, residing at Los Angeles, in the county of Los Angeles and State of California, have invented new and useful Improvements in Adjustable Eye-Tilting Devices for Dolls, of which the following is a specification.

This invention relates more specifically to 10 a device for tilting the eyes in the heads of bisque or composition dolls.

An object of this invention is to provide a simple doll's eye tilting device that is capable of adjustment in the heads of dolls 15 of various sizes.

A further object is to provide an eye tilting device for dolls' heads in which the eyes may be quickly and accurately adjusted laterally to suit the varying widths of a 20 doll's eye sockets.

A still further object is to provide an eye tilting device which can be instantly adjusted so as to limit its tilting movement.

A final object is to produce a device of 25 the class described which may be stamped from a single sheet of flexible metal, which is simple in construction, highly efficient in operation, and unlikely to get out of order or adjustment.

30 I accomplish the above objects by means of the device described herein and illustrated in the accompanying drawings, in which:

Figure 1 is a rear elevation of the front 35 portion of a doll's head of usual construction showing the eye tilting device adjustably mounted therein.

Fig. 2 is a central vertical section taken on line 2-2 of Fig. 1.

40 Fig. 3 is a transverse section taken on line 3-3 of Fig. 2.

Fig. 4 is a perspective view of the eye tilting device.

Fig. 5 is a rear face view of a modified 45 form of eye tilting device, with an eye in position thereon.

Fig. 6 is an enlarged central vertical section through one arm of the tilting device, and one of the eye balls, taken on line 6-6 50 of Fig. 5, looking in the direction indicated by the arrows thereon.

Fig. 7 is an enlarged section taken on one arm of the tilting device through one 55 of the eye balls, taken on line 7-7 of Fig. 5 looking in the direction indicated by the arrows thereon.

Heretofore, owing to slight variations in the width between eye sockets of a doll's head, considerable trouble has been experienced by the makers in adjusting the tilting eyes so that they will present a natural appearance when finally inserted in the head. The usual method employed was to attach each eye to a single piece of wire and to twist the two wires together in the 60 middle, and then adjust the same so as to fit the eye sockets of a doll's head. The twisted wires were then reinforced with a plastic substance, such as plaster-of-Paris, to stiffen the same and also to attach a 65 weight to the center of the twisted wires in order that the eyes would be brought into the proper position when the doll was either 70 in vertical or horizontal position.

By means of the present invention the 75 tilting device is formed of a single piece of sheet metal preferably struck from a die, the eyes being adjustably secured thereto by means of set screws. From this construction it will be noted that by a slight 80 turn of screws either of the eyes may be moved laterally so as to make an accurate instant adjustment, thus obviating all necessity of twisting wires and reinforcing the 85 same with plastic substances.

Referring now more particularly to the drawings, 5 designates the front half of a composition doll's head, the rear half or back of a doll's head not being shown as it forms no part of this invention, the tilting 90 device being secured in the front half and provided with the usual eye sockets 6 and 7.

The tilting device 8 is preferably formed of thin sheet metal formed by means of a die, and consists of laterally extending arms 95 9 and 10, each provided with slots 11 and 12 which terminate at the juncture point of the two arms in a circular aperture 13, the outer ends of the two arms are each provided with a bearing point or trunnion 14 and 15. The 100 edges of the two slots are counter sunk as at 16 so as to provide seats for adjusting screws 17 which maintain the eyes in position on the tilting device, as will be more particularly described hereinafter. Formed integrally at the juncture point of the two arms 9 and 10, is an upwardly extending arm 20 105 designed to limit the movement of the tilting device when the doll is brought to a reclining or horizontal position. This arm 110 may be bent, as clearly shown in Fig. 2 of the drawings, to suit the configuration of the

inner upper portion of the doll's head. Also formed integrally at the juncture point of the two arms and depending downwardly therefrom is another arm 21 provided on the 5 outer end thereof with a weight 22. This arm may also be bent to suit the configuration of the lower portion of the doll's head, as is arm 20, the weight 22 carrying the tilting device to a vertical position so as to show 10 the eyes in an open condition when the doll is turned upwardly to a vertical position.

At one side of the eye socket 6 in the interior of the doll's head is formed a recessed bearing 23 which is engaged by the trunnion 14 of the tilting device, while on the side of socket 7 is formed a slotted recessed opening 24 adapted to seat the other trunnion 15 of arm 9, a small piece of plastic substance or wax 25 being inserted in the slotted opening 20 so as to prevent accidental displacement of the tilting device when in position.

The doll's eyes 25' are here shown as hemispherical in form, preferably formed of celluloid or similar material, and painted on 25 the exterior surface thereof to represent the human eyes. The circular edges of the eyes are bent inwardly as at 26 to form a flange, an apertured threaded washer 27 being seated on the interior surface of said flange for 30 the reception of the adjusting screw 17. Seated on the exterior surface of flange 26 is a metallic washer 28, this washer being apertured and screw threaded, as washer 27, for the reception of the adjusting screws.

35 By means of the above described eye constructions, the eyes may be adjusted laterally in the slots 11 and 12, the heads of the screw passing through the central aperture 13 when attaching the eyes in the slots of the tilting 40 device 8.

From the above description it will be seen that by a slight movement of either eye, the same may be quickly and accurately adjusted to suit the eye sockets of a doll's head, while 45 the trunnions may be clipped off so as to adapt the tilting device 8 for dolls' heads of smaller sizes.

In Figs. 5, 6 and 7 I have illustrated a modified form of tilting device and the manner of adjustably securing eyes on the arms. 50

In the above mentioned construction, the tilting device 30 consists of a vertically disposed bar 31 and cross bars 32 which project at substantially right angles from the vertical bar 31 intermediate its length, the tilting device being of substantially the same configuration as the tilting device in the preferred form heretofore described. The eye constructions illustrated in Figs. 6 and 7 are 55 of substantially the same configuration as the eyes in the preferred form, with the exception that the ball or eye socket 33 on its rear side is provided with an inwardly extending annular flange 34, the outer annular edge of a metal plate 35 contacting with

the inner surface of the flange 34. This plate is preferably provided with a plurality of prongs 36 formed integrally therewith which are bent to engage the annular flange 34 of the eye ball so as to hold the eye ball and the plate in rigid relation to each other. Metal disk 35 is also provided with tongues 37, 38, which are bent outwardly as best shown in Figs. 6 and 7 of the drawings, so as to frictionally engage the arms 32 of the tilting device 30. As the metal disk is formed of spring metal the tongue 37 will frictionally engage the arms 32, and may be slid along arms 32 so as to obtain the proper adjustments of the eye sockets in the doll's head.

By means of this construction I am enabled to dispense with the slots 11 and 12, and the centrally disposed aperture 13 in the tilting device, and also dispense with threaded washers and screws, as illustrated in the preferred form.

What I claim is:

1. In combination with a doll's head having eye openings therein, of an eye tilting device mounted in said doll's head, comprising a slotted bar, the ends of said bar adapted to pivotally engage the interior surface of the doll's head adjacent the eye openings, whereby to impart a tilting motion to said bar on a movement of the doll's head, and a pair of eyes adjustably mounted on said slotted bar.

2. In combination with a doll's head having eye openings therein, of an eye tilting device comprising a slotted bar tiltingly mounted within said doll's head, the ends of said bar adapted to pivotally engage the interior surface of said doll's head adjacent said eye openings, a pair of eyes mounted on 105 said bar, and means to adjust said eyes along said bar.

3. In combination with a doll's head having eye openings therein, of an eye tilting device comprising a slotted bar tiltingly mounted within said head adjacent said eye openings, a pair of eyes mounted on said bar, means to adjust said eyes along said bar, and means to limit the tilting movement of said slotted bar.

4. In combination with a doll's head having eye openings therein, of an eye tilting device comprising a slotted bar pivotally mounted within said head adjacent said eye openings, a pair of eyes mounted on said bar, means to adjust said eyes laterally of said bar, vertically extending arms formed at the center of said bar, one of said arms extending upwardly and the other of said arms extending downwardly therefrom, and a weight secured at the lower end of said lower arm, whereby to cause a tilting movement of the bar on a movement of the doll's head, the upper of said arms adapted to limit the tilting movement of said bar.

5. In combination with a doll's head having eye openings therein, of an eye tilting device mounted within said head comprising a slotted bar, the ends of said bar adapted to pivotally engage the interior surface of the doll's head adjacent the eye openings, and a pair of eyes adjustably mounted on said slotted bar, a weight bar formed integrally with said slotted bar for tilting said bar when the doll's head is moved from one position to another, and means to limit the tilting movement of said bar. 25
6. In combination with a doll's head having eye openings therein, of an eye tilting device mounted within said doll's head comprising a bar, the ends of said bar adapted to pivotally engage the interior surface of a doll's head adjacent the eye openings, and a pair of eyes adjustably mounted on said bar. 30
7. In combination with a doll's head having eye openings therein, of an eye tilting device mounted within said doll's head comprising a weighted bar, the ends of said bar
- adapted to pivotally engage the interior surface of a doll's head adjacent the eye openings, and a pair of eyes slidingly mounted on said bar. 35
8. In combination with a doll's head having eye openings therein, of an eye tilting device mounted within said doll's head, comprising a slotted bar having a downwardly extending weighted arm depending from the center of said bar, whereby to cause a tilting movement of said bar on a movement of said doll's head, the ends of said bar being formed into pivotal points and engaging the interior surface of said doll's head, a pair of eyes secured to said slotted bar, screws for rigidly securing said eyes to said slotted bar when the same are brought to the adjusted position, and means to limit the tilting movement of said bar. 40

In witness that I claim the foregoing I have hereunto subscribed my name this 28th day of May, 1918.

WARREN G. KELLOW.
